[57] **ABSTRACT**

A double bed is convertible into twin sofas having a common back and disposed back to back. Headboards and footboards of the bed form end arm supports for the sofas.

1 Claim, 5 Drawing Figures

PATENTED JUN 13 1972

FIG. 1

FIG. 2

FIG. 4

FIG. 3

FIG. 5

INVENTOR.
ADDIE B. ROMERO

CONVERTIBLE SOFA BED

SUMMARY OF THE INVENTION

A horizontal frame of fixed length can be adjusted in width between two positions. In fully extended position, three mat like sections can be disposed horizontally side by side to define a double bed. In partially extended position, the middle section can be disposed vertically between the two outer sections whereby two sofas are formed which are disposed back to back and utilize the middle vertical section as a common back. 10

The frame can have headboards and footboards which serve as end disposed arm rests when the double sofa form is used. These head and footboards can be used as a snack bar. 15

BRIEF DESCRIPTION OF THE DRAWINGS

In the drawings:

- FIG. 1 is a perspective cut away view of my invention;
- FIG. 2 is an end view thereof;
- FIG. 3 is a detail cross sectional view thereof;
- FIG. 4 is another detail view thereof; and
- FIG. 5 is a perspective view of my invention as used in sofa form.

DETAILED DESCRIPTION OF PREFERRED EMBODIMENTS

Referring now to FIGS. 1-5, horizontal parallel elongated cushion straps 10 extend between parallel transversely extending front and rear members 12 slidable toward and away from each other in racks 14 in headboard 16 and footboard 18. When the members 12 are extended to maximum separation, oppositely extendable horizontal support bars 20 can bridge the gap. Under these conditions, three mat-like sections 22 can be placed horizontally side by side on top of the straps to define a double bed, the boards 16 and 18 functioning in conventional manner. 30

When the members 12 are retracted to minimum separation, the middle section must be disposed vertically as a common back for the two sofas as shown. Under these conditions, head and footboards serve as end arm rests as shown. Each of these boards has a hollow concealed compartment 24 with top disposed access lids 26 which can be opened or closed. These compartments can hold liquors 28, glasses 30 and the like. 40

While I have described my invention with particular reference to the drawings, such is not to be considered as limiting its actual scope. 45

Having thus described this invention, what is asserted as new is:

1. Apparatus convertible between a double bed configuration and a twin sofa configuration comprising frame means having a fixed length and including means to vary the width of the frame, said frame means comprising first and second parallel, vertically disposed headboards, 55 said headboards horizontally disposed from each other

by a fixed distance, four legs supporting each headboard, four horizontally disposed elongated tracks, two of said tracks being mounted on each of said first and second headboards near the bottommost portion thereof so that the outer ends of the tracks do not protrude beyond the outer ends of the headboards, said two tracks on said first headboard facing the two tracks on said second headboard, each of said tracks having a T-shaped slot extending longitudinally throughout its length,

four parallel horizontally disposed spaced apart support bars of equal length, each bar being connected at one end to the bottommost portion of the tracks mounted on said first headboard and at the other end to the bottommost portion of the tracks mounted on said second headboard to maintain said headboards in fixed, spaced parallel relationship, two of the support bars being located at the outer ends of the first and second headboards,

parallel, elongated, and horizontally disposed cushion straps connected at their one end to the tracks of the first headboard and at their other end to the tracks of the second headboard,

said means to vary the width of the frame being movable between a fully extended position and a retracted position and including

four elongated members, one member being associated with each of said four tracks, each member having a T-shaped lateral extension extending longitudinally along one side of the member, said extension interfitting with the T-shaped slot in the associated one of said tracks so that the members are supported by and longitudinally movable along the tracks to the extended position and the retracted position,

parallel, elongated and horizontally disposed cushion straps connected to and extending between opposite ones of the members supported by opposite tracks; and first and second outer mat-like sections and an inner mat-like section, each section being freely and independently movable with respect to each other and the frame, said sections supported by said frame,

said three mat-like sections each having a length equal to the distance between the opposing headboards and a width equal to one-third the fully extended width of the frame,

said means to vary the width of the frame being movable to the fully extended position defining a double bed configuration wherein the three mat-like sections are horizontally disposed and adjacent each other,

and to the retracted position defining a twin sofa configuration wherein the first and second outer mat-like sections are horizontally disposed and the inner section is vertically disposed and interposed between the first and second outer sections.
